CLAIM

The ornamental design for a lens for camera, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a perspective view of a lens for camera showing my new design;

FIG. 2 is a front view thereof;

FIG. 3 is a rear view thereof;

FIG. 4 is a top plan view thereof, the bottom plan view being a mirror image of the top view;

FIG. 5 is a right side view thereof; and,

FIG. 6 is a left side view thereof.

The broken lines depict portions of the lens for camera in which the design is embodied that form no part of the claimed design.
